UNITED STATES PATENT OFFICE

106,108

DESIGN FOR A RECORDING KEY FOR VENDING APPARATUS

David J. Conant and Sam Esgro, Memphis, Tenn.

Application February 24, 1937, Serial No. 67,830

Term of patent 14 years

To all whom it may concern:

Be it known that we, David J. Conant, a citizen of the United States of America, residing at Memphis, in the county of Shelby and State of Tennessee, and Sam Esgro, a citizen of Italy, residing at Memphis, in the county of Shelby and State of Tennessee, United States of America, have invented a new, original, and ornamental Design for Recording Keys for Vending Apparatus, of which the following is a specification, reference being had to the accompanying drawing forming part thereof.

Fig. 1 is a perspective view of a recording key for vending apparatus, showing our new design.

Fig. 2 is a plan view.

Fig. 3 is a side elevation; and

Figs. 4 and 5, end elevations.

The numerals appearing in Figs. 1, 2 and 3 vary in the operation of the device and as here shown are merely representative.

We claim:

The ornamental design for a recording key for vending apparatus, substantially as shown and described.

DAVID J. CONANT.
SAM ESGRO.
